Eugene C. Bernheim Inventor

By Attorney

UNITED STATES PATENT OFFICE.

EUGENE C. BERNHEIM, OF SOUTHBIDGE, MASSACHUSETTS, ASSIGNOR TO OPTICAL SPECIALTY MANUFACTURING COMPANY, OF SOUTHBIDGE, MASSACHUSETTS, A CORPORATION OF RHODE ISLAND.

EYEGLASSES.

1,320,360.

Specification of Letters Patent. Patented Oct. 28, 1919.

Application filed October 9, 1917, Serial No. 195,601. Renewed April 17, 1919. Serial No. 290,903.

To all whom it may concern:

Be it known that I, EUGENE C. BERNHEIM, a citizen of the United States, residing at Southbridge, in the county of Worcester, 5 and State of Massachusetts, have invented certain new and useful Improvements in Eyeglasses, of which the following is a specification.

My invention relates to improvements in 10 eyeglasses and refers particularly to the type or character of eyeglasses known as finger lever eye-glasses.

In eye-glass mountings of the finger lever type and in general and common use having 15 long tubular bearings it has been found that the oleaginous matter from the skin induced by perspiration becomes deposited upon and between the two tubular bearings of the mounting forming a thick coagulated 20 substance which in time covers or coats said bearings and considerably reduces the efficiency and proper easy action of the parts and further destroys the resiliency or quick action of the actuating 25 springs, due to the congealing of the said matter between the two tubular bearings.

The main object of my invention is the provision of an eye-glass mounting employing tubular bearings which will convey the 30 said coagulated matter away from between the bearing faces of the tubular bearings and prevent its coagulating at points which would impede or interfere with the action of the springs or the proper movement of the 35 tubular bearings, thus overcoming the serious defect and objection noted.

Other objects of my invention are the provision of an eye-glass mounting of extremely 40 simple construction whose parts may be quickly assembled with the fingers; in which absolute accuracy and automatic alinement of the parts are assured; which provides a broad bearing surface for the telescoping cylinders and prevents undue strain or wear 45 upon individual parts; and which requires practically no time-wasting adjustment of parts to insure absolutely perfect lens alinement.

Still further objects of the invention are 50 the provision of a mounting which will have a greater amount of bearing surface than ordinary mountings of this character; which will eliminate entirely the strain or wear upon the pivot screw; which will reduce the

friction on all parts to a minimum, and thus 55 all things considered produce a mounting of this type which will be thoroughly efficient and practical from every point of view.

With these objects in view the invention, broadly stated, consists of an eyeglass 60 mounting having finger levers formed with tubular bearings, pivots for said bearings, and a chamber or pocket disposed between the tubular bearings and posts to receive and retain the oleaginous matter and prevent its 65 coagulation between said posts and tubular bearings.

The invention further consists of an eyeglass mounting embodying novel features of construction and combination of parts for 70 service substantially as shown, described and particularly defined by the claims.

In order that the details of construction and operation of my mounting may be understood and its many advantages be appreciated, I have shown in the accompanying drawing an eyeglass mounting constructed according to my invention.

Figure 1 is a front elevation of an eye-glass mounting constructed in accordance 80 with and embodying my invention.

Figs. 2, 3, 4, 5, 6, 7 and 11 are sectional views of modified forms of my improvement.

Fig. 8 is a detail view illustrating the evolutions in the method of forming the 85 tubular bearing on the tables of the bridge.

Fig. 9 is a detail view of one of the guard levers, showing the evolutions from flat metal in producing the drawn up tubular bearings 90 to fit upon the tubular bearings shown in Fig. 8, and

Fig. 10 shows the blank metal before and after the guard lever has been blanked out and superfluous metal has been removed.

In the drawings:

The letter A designates the lenses; B the clips; C the straps; D the bridge formed with the tables E, and F the finger levers which carry guards.

I have in this application shown a number 100 of forms or modifications of my invention, any and all of which perform their functions in the same manner, and each and all of which have embodied therein bearing posts G, having a threaded end G' seated in 105 threads H, of the tables of the bridge and formed with a chamber G² or employing upon the levers tubular bearings J fitting on

15 manner of making the tubular bearing an integral part of the stock of the bridge and lever which is the preferred manner of making this tubular bearing, and which is accomplished by punching, stamping or drawing out the tubular bearing direct from the stock of which the levers and bridge are 20 made, thus avoiding soldering or brazing which weakens the stock and retaining unimpaired the original stiffness of the metal.

25 The several forms or modifications shown illustrate practical structures for carrying my invention into effect, but I wish it understood that the main and essential feature of my invention consists in the location of a chamber between the rigid bearing or support and the tubular bearings on the levers, 30 which would act to collect the matter from the skin induced by respiration, and for a long period of time prevent its accumulation or clogging, as at present, owing to the limited space between the posts and tubular 35 bearings, which accumulation more quickly destroys the resiliency or quick action of the springs.

40 It will also be noted that my improvements provide bearings at the top and bottom producing bearings having less friction than the tubular bearings made of continuous metal and thereby forms the cavity or chamber as before noted.

45 The efficiency and more extensive sale and use of finger lever eyeglasses has in the past been greatly retarded, owing to the accumulation of the deposits of coagulated matter which accumulates upon the movable parts, and this disadvantage is greatly overcome 50 by my invention.

I claim:

1. An eye-glass, consisting of lenses, bridge and levers carrying guards, supports carried by the bridge, tubular bearings car-

pivots and tubular bearings to form receptacles.

4. An eye-glass, consisting of the lenses, 70 bridge and lever carrying guards, posts rising from the bridge and each formed with a head, tubular bearings carried by the levers and pivoted on the posts, a chambered portion between the posts and tubular bearings 75 and actuating springs coiled around the tubular bearings and retained in position by the heads on said posts.

5. An eyeglass, consisting of lenses, bridge, supports mounted in said bridge, levers having tubular bearings fitting on said supports, a chamber disposed between the said supports and bearings, and actuating springs for the levers disposed upon said tubular bearings. 85

6. An eyeglass, consisting of lenses, bridge, supports mounted in said bridge and formed with a head, guard carrying finger levers having tubular bearings mounted on said supports, a chamber between said supports and tubular bearings, and actuating springs for the levers disposed upon said 90 the heads of the supports.

7. An eyeglass, consisting of lenses, bridge connection, vertical supports on said 95 bridge connection, levers carrying guards and having tubular bearings mounted on the vertical supports, and means between the supports and tubular bearings to receive secretions or discharged matter from the 100 skin of the nose.

In testimony whereof I affix my signature in the presence of two witnesses.

EUGENE C. BERNHEIM.
